Usua & Rauber

his Attorneys.

UNITED STATES PATENT OFFICE

CHAUNCEY MARSH GOODRICH, OF WINDSOR, ONTARIO, CANADA

SCAFFOLD

Application filed September 9, 1929. Serial No. 391,359.

This invention relates to scaffolds, and more particularly to hanging scaffolds for use in erecting tier buildings, and has for its object the provision of a scaffold construction which may be readily assembled in position, is durable, and forms a permanent tool that may be used over and over wherever needed.

When erecting bridges, the structural steel work for buildings and the like, it is customary to swing ropes from four points about the beams, and to connect these ropes into pairs by needle beams or timbers and then to bridge the timbers with planks, thus forming a swinging platform or scaffold on which the workmen can stand. The assembly of a scaffold by the use of ropes, timbers and planks as described above is slow and expensive, and even at best such scaffolds are not safe.

20 The scaffold of this invention may be assembled in much less time than the scaffold of the prior art, it is strong and safe and such scaffolds are much cheaper to use since less labor is required to assemble and dismantle the scaffold, and also due to the fact that the scaffold can be used over and over again.

In the drawings:

Figure 1 is a plan showing the scaffold of this invention in position on a building structure or the like.

Figure 2 is an enlarged detail of one of the hangers of the scaffold.

Figures 3 and 4 are sectional views taken on the lines III—III and IV—IV of Figure 2, respectively.

Figure 5 is a fragmentary view showing the hook or top end of one of the hangers.

Referring more particularly to the drawings the letter A designates the column of a building or other structure, and the letter B designates the horizontal beams supported by the column.

45 The scaffold of this invention is adapted to be hung or suspended from the beams B and comprises hangers C arranged in pairs and adapted to support a removable plank floor or platform D.

The hangers C are each composed of a vertical support or leg 2 in the form of a length

of rolled angle-bar which is provided at its upper end with a hook member 3 welded in position and forming a permanent part of the leg.

The legs or supports 2 have their flanges 6 provided with a series of vertically spaced holes 4 to receive bolts 5 used to secure lugs 6 in position on the legs 2. The lugs 6 are formed from a short section of angle-iron and are arranged to extend parallel with the legs 2. A filler block 7 is secured to each of the lugs 6 and extends from their lower ends upwardly to a point adjacent their upper ends so as to space the upper ends of the lugs from the legs. The lugs 6 are adapted to be mounted at selected vertical positions on the legs 2 by mounting the bolts 5 in selected ones of the holes 4.

The hangers of each pair are connected together by a horizontal angle-bar 8 having one of its flanges inserted in the space between the upper part of the lugs 6 and the legs 2 and having its other flange extending horizontally over the top of the lugs 6.

Suitable planks 9 are adapted to be bridged across and supported on the bars 8 of each pair of hangers to form a platform upon which the workmen may stand.

The bars 8 are provided with a series of holes 10 adjacent each end in which a suitable bolt or pin 12 may be removably mounted to form a stop to prevent the planks 9 from slipping off of the bars 8 when it is necessary to mount said planks outside of the hangers C.

When using the scaffold of this invention it is only necessary to mount the hangers C on the beams B and then mount the bars 8 on the pairs of hangers C and then place the planks 9 across the bars 8 to form the platform. When dismantling the scaffold the planks are first removed, then the bars 8, and finally the hangers are bodily removed.

While I have shown and described one specific embodiment of my invention it will be understood that I do not wish to be limited thereto since various modifications may be made without departing from the scope of my invention, as defined in the appended claims.

I claim:

1. A scaffold construction comprising two spaced pairs of rigid hangers, each of said hangers comprising a vertically disposed angle-iron support, a hook member fixedly secured to the upper end of said angle-iron support and having its hooked end extending downwardly and outwardly on an angle to the longitudinal axis of said support, said angle-iron support having its flanges provided with a series of vertically spaced holes, a lug removably secured to said support by bolts mounted in selected ones of said holes, said lug extending parallel with said support and having its upper end spaced from said support, a horizontal bar bridging the space between and connecting the hangers of each of said pairs of hangers, said bar being mounted in the spaces between said lugs and said supports, said bars being provided with a plurality of spaced apertures adjacent each end, pins mounted in selected ones of said apertures in said bars at each side of said lugs to prevent longitudinal movement of said bars relative to said lugs, and planking bridging the space between said pairs of hangers and supported on said horizontal bars.
2. A scaffold construction comprising two spaced pairs of rigid hangers, each of said hangers comprising a vertically disposed angle-iron support, a hook member fixedly secured to the upper end of said angle-iron support and having its hooked end extending downwardly and outwardly on an angle to the longitudinal axis of said support, said angle-iron support having its flanges provided with a series of vertically spaced holes, a lug removably secured to said support by bolts mounted in selected ones of said holes, said lug extending parallel with said support and having its upper end spaced from said support, a horizontal angle bar bridging the space between and connecting the hangers of each of said pairs of hangers, said bar having one flange extending over the top face of said lugs and having its other flange inserted in the spaces between said lugs and said angle-iron support, said bars having their flanges extending over the top faces of said lugs provided with a plurality of spaced apertures adjacent each end, pins mounted in selected ones of said apertures in said bars at each side of said lugs to prevent longitudinal movement of said bars relative to said lugs, and planking bridging the space between said pairs of hangers and supported on said horizontal bars.

In testimony whereof, I have hereunto set
60 my hand.

CHAUNCEY MARSH GOODRICH.
